UNITED STATES PATENT OFFICE.

CHARLES J. MELBY, OF EVERETT, WASHINGTON.

SHINGLE-PLANING MACHINE.

Application filed June 9, 1926. Serial No. 114,618.

This invention relates to a machine for planing taper-sawed shingles and, more especially, for surface grooving the same to produce what is known as shake-shingles.

6 The object of the invention is the improvement of machines of the character above referred to.

In the accompanying drawing,

Figure 1 is a plan view, with parts broken away, of a shingle planing machine embodying my invention; Fig. 2 is a longitudinal vertical section of Fig. 1 and illustrating a shingle applied; and Fig. 3 is a transverse section on line 3—3 of Fig. 2. Fig. 4 is a 10 plan view of the shingle-grooving cutter knife, shown detached. Fig. 5 is a perspective view of a grooved shingle as produced by the shake-shingle machine illustrated in the preceding views.

20 The machine frame 10 may be of any suitable construction and, as illustrated, includes longitudinal side rails 11, supporting legs 12, and spaced apart bed plates 13 and 14 which are rigid with said side rails at 25 the respective ends of the frame.

15 represents a horizontally disposed cutter head whose arbor 15¹ is journaled in bearing boxes 15² secured to said side rails 11 in proximity of the inner edge 14¹ of the 30 bed plate 14. Upon one of its peripheral surfaces said head has secured thereto a cutter knife 16 which, as shown in Fig. 4, is provided in its outer surface with a series of alternating ridges and grooves 18, parallel with each other and in rectangular relation to the axis of their revolution.

Said knife is beveled at its front, or leading side, to afford a cutting edge 19 at the intersection of the plane of such front side 40 with the corrugated surface of the knife. In practice, the weight of the knife 16 is balanced by a counterweight or, as shown, by means of a second knife 20 which is not provided with corrugations and has a 45 straight cutting edge.

By adjusting the knives with respect to each other and to the work, either knife may be utilized for cutting separately but not together, such for instance, as when planing 50 a plane surface, the knife 20 would be regulated to have its straight cutting edge travel in an orbit of larger diameter than the orbit to which the irregular cutting edge 19 of the knife 16 is positioned; and, vice versa, when 55 the knife 16 is to be employed for grooving a shingle.

The cutter head 15 is driven by means of a belt 22 passing about a pulley 23 which is mounted upon the arbor 15¹. Positioned in the opening between the cutter head 15 and the bed plate 13 and constituting, in effect, a continuation of the latter, is a plate 24, hereinafter designated as the lifting plate, which is hingedly connected at its front end to the machine frame as by means of a pivot 60 rod 25 extending through apertured lugs, such as 26, of the lifting plate.

27 represent springs interposed between a bridge member 28 of the machine frame and the free end of the lifting plate, said 70 springs tending to yieldingly retain the lifting plate in its uppermost position. The elevation of the lifting plate is limited by the provision of stops 29, such as nuts, taking upon threaded bolts 30 depending from 75 the lifting plate through holes provided in the bridge member 28 and arranged to engage against the latter.

Supplementary to and located above the lifting plate 24 is a pressure plate 31 of 80 a length to extend above the bed plate 14 to the rear of the cutter head. Said pressure plate is formed or provided with transversely arranged reinforcing bar elements 31¹ having at each side of the plate proper apertures through which respectively extend vertical guide rods 32 rigid with the frame. 85

These rods are screw threaded to receive nuts 33 below the presser plate bar elements to limit the downward movement of the same. 90

Threaded upon these guide rods above the presser plate are nuts 34 for confining springs 35 which are mounted upon the rods and act to yieldingly retain the presser plate against the stops 33. 95

37 represent endless chains, one at each side of the machine, passing about sprocket wheels 38 and 39 and through guiding channels 40 mounted upon the respective side rails 11 of the machine frame. 100

The sprocket wheels 38 and 39 are respectively mounted upon shafts 38¹ and 39¹ which are journaled in bracket boxes 48 or an equivalent provided on the frame.

Transversely arranged attachments 41 are 105 connected to said chains to effect the feeding of the work when the chains are driven as by means of a power belt 42 passing about a pulley 43 provided therefor on the shaft 39¹.

The character of the work performed in 110 the machine by the fluted cutter knife 19 is illustrated in Fig. 5 and is known in the art.

as a shake-shingle. This type of shingle is produced from a taper-sawed shingle having upper and lower plane surfaces by cutting grooves 44 longitudinally of the shingle in one of its surfaces, said grooves extending from the butt end of the shingle to within a short distance of the shingle point 45, the ungrooved plane portion 46 of such surface being intended to underlie the butt end 10 of the shingle in a course next above in the shingling of a roof.

In operation, a shingle, as indicated by S, placed with its point in front upon the bed plate 13 will be engaged at its butt end by 15 an attachment 41 of the feed chains 37 to be propelled thereby.

The shingle is thus fed point first upon the lifter plate 24 keeping the shingle above the cutting circle of the cutter and against 20 the under surface of the presser plate 31.

When in its continued travel the thickness of the shingle above the cutter head exceeds the space between the presser plate and the cutting circle, the planing of the shingle 25 occurs and continues until the butt end of the shingle has passed beyond the cutter head. When a plane cutting knife, as explained with reference to the knife 20, is employed the surface of the shingle acted upon will be finished to a plane; but when 30 the fluted cutter knife 16 is employed the shingle surface acted upon will be grooved as represented in Fig. 5.

By regulating the operating cutter knife 35 to have its cutting edge revolve in a cutting circle of more or less diameter, the extent of the protrusion of the cutting circle above the plane of the upper surface of the frame-plate 14 will determine the depth cut into a 40 shingle.

It is to be noted that the presser plate 31 is supported by the stops 33 (Fig. 3), and that the presser plate is yieldingly held in operable position by means of springs 35 45 located at both sides and in proximity with both ends of the presser plate. The springs 35 which actuate the presser plate are of greater power than the springs 27 which 50 actuate the lifter plate. In practice a shield plate 50 is desirably provided to protect the springs 27 from shavings projected by the cutter knife.

What I claim, is,—

1. In a shingle-planing machine, a rotary cutter-head, a grooved planer knife mounted 55 upon said cutter-head, means to progressively feed a shingle upon the machine, spring pressed lifting means acting to elevate a shingle out of the cutting region of said planer knife until after an end portion of 60 the shingle has traveled beyond said cutting region, and a spring pressed means engageable by the shingle to effect movement of the shingle into said cutting region for grooving the shingle from said portion to 65 the other end of the shingle.

2. In a shingle-planing machine, a cutter-head, a planer knife therefor, said planer knife being grooved upon its outer side with respect to the cutter-head, shingle feeding 70 means, means to elevate the point end of a shingle out of cutting relation with said planer knife, and means acting subsequently to the aforesaid means to regulate the shingle to have its under-surface grooved by the 75 planer knife.

3. In a shingle-planing machine, the combination with the machine frame including a top comprising two horizontally spaced apart bed elements, and a rotary cutter 80 located between said bed elements, of a presser plate located above the cutter and provided with guideways, posts extending upwardly from said frame through said ways for guiding the presser plate, means 85 adjustable upon the respective posts to limit the downward movement of said plate, springs mounted upon said posts for yieldably retaining the plate in its lowermost position, a lifter plate hingedly connected 90 to said frame and having its free end extend into the space beneath said presser plate, resilient means tending to retain the free end of the lifter plate in its uppermost position, said presser plate and lifting plate 95 being arranged to be influenced by the feeding of a shingle therebetween to raise and lower the same into cutting relation with said cutter, and means to effect the feeding of the shingle.

Signed at Seattle, Washington, this 20th day of April, 1926.

CHARLES J. MELBY.
